His Attorney.

UNITED STATES PATENT OFFICE.

ALBERT W. HULL, OF SCHENECTADY, NEW YORK, ASSIGNOR TO GENERAL ELECTRIC COMPANY, A CORPORATION OF NEW YORK.

ELECTRON DEVICE AND METHOD OF OPERATING.

Application filed November 15, 1921. Serial No. 515,410.

To all whom it may concern:

Be it known that I, ALBERT W. HULL, a citizen of the United States, residing at Schenectady, in the county of Schenectady, State of New York, have invented certain new and useful Improvements in Electron Devices and Methods of Operating, of which the following is a specification.

The present invention comprises an improved electrical device belonging to the general class of devices known as "magnetrons," which are described by me in the Journal of the American Institute of Electrical Engineers, September, 1921, Vol. XLI, 15 page 627.

A magnetron comprises an electron-emitting cathode and an anode arranged in such relation to each other that a current between these electrodes may be varied or interrupted by a suitably applied magnetic field. For example, the cathode may consist of a simple linear filament and the anode consist of a conducting cylinder symmetrically arranged about the cathode filament. In magnetrons now being used as radio detectors the controlling magnetic field is parallel to the cathode and is generated by an electrical winding surrounding the magnetron tube. Assuming a given voltage to be applied to the cathode and anode and the magnetic field value to be progressively increased from zero, the electron or space current in the tube at first is substantially unaffected over a range of field values; then as the magnetic field exceeds a critical value, depending on the characteristics of a particular device and the applied voltage, the electron current rapidly decreases, and finally with a sufficiently high field value the electron current becomes zero.

When the diameter of the cathode filament is relatively small the magnetic field of the cathode current may be neglected. For example, when in a magnetron radio detector the tungsten cathode has a diameter of about 5 mils, the heating current is insufficient to reduce the electron current no matter how small the applied voltages may be, in fact, the initial emission velocities of the electrons even when no voltage is applied will overcome the deflection force of the current ordinarily required to render incandescent a filament of this size. When the applied voltage is as low as about one volt, the heating current in a filament of seven

mils diameter is sufficient to produce an appreciable decrease of electron current, by what I term an axial magneto-strictive effect. The term "magneto-strictive effect" may be used in a broad sense to refer to the limitation of an electron current by a magnetic field. An axial magneto-strictive effect in a more restricted sense designates the controlling effect upon an electron current exerted by a magnetic field, the lines of force of which are oriented in planes substantially at right angles to the axis of the device. In a device in which an axial magneto-strictive effect is exerted by a current flowing through one of two substantially parallel conductors, the control of the current is produced by the bending of the paths of the electrons by the magnetic field so that the electrons emitted by one electrode fail to reach the second electrode. In the case of concentric conductors and in the absence of any other magnetic field the paths of these electrons will be in planes passing through the axis of the current carrying conductor. In general, the voltage necessary to overcome the magneto-strictive effect of a current required to render incandescent a tungsten filament, is substantially proportional to the cube of the diameter of the cathode.

In accordance with one feature of my present invention, I have provided electron discharge devices of the magnetron type utilizing the axial magneto-strictive effect. The preferred embodiment of my invention contains a cathode having a current carrying capacity sufficiently high to conduct currents capable of producing a magnetic field whereby the electron current may be varied, or even entirely interrupted. I have also devised new methods and apparatus for utilizing electronic devices operating with magneto-strictive current control.

The novel features of my invention will be pointed out with greater particularity in the appended claims. A more detailed description of my invention is contained in the following specification taken in connection with the accompanying drawings in which Fig. 1 is a perspective view of one end of a magnetron embodying my invention; Fig. 2 is a graph showing the relation between the current traversing the cathode and the space current between the electrodes; Fig. 3 is a diagram of an amplifier

system embodying my invention; Fig. 4 diagrammatically illustrates a system utilizing my new device for either rectifying alternating current or converting direct to alternating current; Fig. 5 is a graph showing electrical characteristics of the apparatus shown in Fig. 4; Fig. 6 is a diagram of a radio system containing a magnetron embodying my invention; and Fig. 7 is a graph of magnetic and electrical characteristics of a device such as shown in Figs. 3 and 6.

In devices suitable for use with commercial voltages I have employed tungsten cathode conductors having a diameter at least several fold greater than 7 mils at which the control of electron current by the magnetic field of the cathode begins to be effective. For example, with an applied voltage of about 60 to 80 volts, I have used as cathode a tungsten wire of about 40 mils diameter. When the applied voltages are as high as about 1000 volts the cathode diameter should be about 100 mils and when the applied voltages are as high as 10,000 volts, a 200 mil tungsten conductor is required. When a cathode material is employed having a materially greater or lesser conductivity than tungsten, the cathode diameter, of course, will correspondingly depart from these dimensions.

To carry the heavy currents into the evacuated container, special circuit connections should be provided to obviate cracking of the seal at the cathode terminals as the cathode expands and contracts. Fig. 1 shows one end of a tube embodying my invention in which a linear cathode 8 is connected to a conductor 9 sealed into the envelope 10. The end of the cathode 8 which preferably consists of tungsten is joined by swaging or otherwise to a sleeve of molybdenum, the latter is screw-threaded and inserted into a threaded socket 11 preferably consisting of copper. A spring consisting of tungsten connects the socket 11 with a similar socket 12 at the end of the conductor 9. Flexible copper conductors 13 connect the sockets 11 and 12 to convey the greater part of the heating current to the cathode. A cylindrical anode 14 consisting of molybdenum, copper, tungsten or other suitable material symmetrically surrounds the cathode. This anode may be anchored frictionally to the envelope 10 by a coiled wire 15. As the opposite end of the device is similarly constructed and these specific structural features do not in any event constitute the present invention, only a part of the device has been illustrated. The construction and evacuation of magnetron devices is described in my above-mentioned publication in the Journal of the American Institute of Electrical Engineers.

65 In Fig. 2 the values of electron currents at

a constant applied voltage are plotted as ordinates and the cathode currents are plotted as abscissæ. Up to a heating current having a value C_1 the electron current between the electrodes 8 and 14 for a given voltage is substantially unaffected. An increase of cathode current above C_1 produces a rapid decrease of electron current by causing the electrons to be deflected in curved orbits lying in planes passing through the axis of the cathode. At a value C_2 the electron current has fallen to zero.

When the cathode current varies between the value C_1 and C_2 , the electron current will also vary. As shown in Fig. 3 this property of my new device may be utilized to amplify a variable current. The input circuit 16, 17, which is connected to the cathode terminals, contains a direct current source, as for example, a battery 18, and also a source of alternating current, as for example, the secondary of a transformer 19. The output circuit 20, 21 connected to the electrodes 8 and 14 also contains a source of direct current, as for example, a generator 22. The figure also includes a transformer 23, having a primary winding fed by the output circuit 20, 21, but this may be omitted.

In the system shown in Fig. 3 a sufficient current to furnish a field capable of effectively reducing the current in the circuit 20, 21 is furnished by the battery 18 and superimposed on this is the alternating current furnished by the transformer 19. The relation between the magnetic fields and the electron current will be better understood by reference to Fig. 7. The magnetic field about the cathode 8 generated by the direct current source 18 is represented in this figure by a dotted line H_0 , the ordinates representing magnetic field values and the abscissæ time. The superimposed alternating field is represented by the dotted line H_1 . This gives rise to a resultant variable field represented by the full line H . When the magnetic field falls below the value at which the electron current is cut off, current begins to flow in the circuit 20, 21, as represented by the dot and dash curve C of Fig. 7. It will be observed that the current rises rapidly to a maximum as the magnetic field decreases then remains substantially constant, and as the magnetic field rises the current again falls to zero. During the interval when the magnetic field is a maximum no current flows in the circuit 20, 21. In some cases the direct current source 18 may be omitted. In that case the current in the output circuit 20, 21 will have double frequency of the current in the circuit 16, 17. Sufficient current should be furnished by the transformer 19 to heat the filament to incandescence and to generate a controlling field.

65 When the system shown in Fig. 4 is used

to rectify alternating current, then the anodes of the magnetrons 25, 26 are respectively connected to opposite terminals of the secondary of a transformer 27, the 5 cathodes both being connected to a direct current circuit 28, which in turn is connected to a neutral point of the transformer secondary and contains a load 29. The cathodes of the magnetrons 25, 26 are supplied with current respectively by the 10 secondaries of the transformers 30, 31. The primaries of these transformers are supplied by the mains 32 in common with the primary of the transformer 27. Except for 15 the magnetic fields of the cathode currents, the rectifier system illustrated corresponds closely to a standard kenotron rectifier system in which rectification occurs due to unilateral conductivity in a vacuum between 20 an incandescent cathode and an anode operating below a temperature at which electron emission is appreciable. Due to the deflection of the electrons by the magnetic fields about the cathode in the magnetron 25 rectifiers it is necessary to reduce or cut off 25 the cathode current to enable electrons to flow to the anode.

Current is alternately interrupted in the cathode circuits of the magnetrons 25, 26 by some suitable device, as for example, a 30 rotating switch 33 driven by a motor 34 in synchronism with the alternations of the current in the circuit 32. For example, the motor 34 may be supplied with energy from 35 the mains 32 by conductors 35 and a transformer 36. The rotating switch shown in the drawing has a conducting segment and an insulating segment properly proportioned. During one-half cycle, current can 40 flow through the conductors 40, 41 to the cathode of the magnetron 26 setting up a magnetic field about the cathode sufficient to cut off space current flow between cathode and anode. During the other half cycle 45 no current flows through the cathode but the cathode remains at a sufficiently high temperature to supply electrons for conducting a current through the tube to the load. The relation between the cathode current 50 and the electron current is best shown by Fig. 5. During the interval of flow of cathode current (indicated by full lines) no current could flow between the electrodes through the magnetron since the voltage of 55 the anode is negative with respect to the cathode, as indicated by the dotted curve, but during the next half wave of zero cathode current when no magnetic field is present, a space current flows, as indicated 60 by a full line curve.

When a source of unidirectional current is substituted for the load device 29 (the negative terminal being connected to the conductor 28) and the switch 33 is driven 65 at a desired frequency, for example, by

supplying the motor 34 from an independent source of alternating current, then impulses of current are delivered through the magnetrons alternately to opposite terminals of the transformer 27, the winding 70 connected to the magnetron then becoming the primary and alternating current being delivered from the secondary to the circuit 32. In this case it is solely the current limiting effect of the magnetic 75 field of the cathode current which controls the space current flow through the magnetrons as otherwise current would pass at the same time through both tubes and no transformation would occur. 80

Fig. 6 shows a system adapted to furnish oscillating current for radio sending purposes and containing a magnetron embodying my present invention. The cathode 8 is supplied with current from a direct current source, represented by a battery 45, a choke coil 46 being included in the cathode circuit 47 to exclude high frequency. The input circuit 48, 49 which is connected to the electrodes 8, 14, contains a direct current generator 50, preferably shunted by a condenser 51. The output circuit 52 which preferably contains a variable inductance 53 is coupled to the circuit 48 by a transformer 54 and terminates in an antenna 55. 85 The primary winding of the transformer 54 preferably is shunted by an adjustable condenser 56. The load circuit 52 is connected to a grounded conductor 57 through the cathode. As the load current builds 90 up the magnetic field about the cathode increases until it reaches a value sufficient to interrupt the current. Due to this unstable characteristic a surging or oscillating condition is produced, the frequency of the 95 resulting oscillations depending on the capacity and the inductance of the antenna circuit. 100

What I claim as new and desire to secure by Letters Patent of the United States, 110 is:—

1. An electron discharge apparatus comprising means for producing an electron discharge and for generating a magnetic field substantially at right angles to the 115 axis of said discharge within a range in which said electron discharge is varied by said magnetic field, and means for varying said field.

2. The method of controlling an electron 120 discharge which consists in generating in the path of said discharge a magnetic field at right angles to the axis of said discharge, and varying said field above a critical value at which said field is capable of effectively 125 decreasing said discharge.

3. The method of controlling an electron 130 discharge between an electron emitting cathode and a cooperating electrode which consists in generating a magnetic field at

right angles to said cathode of sufficient magnitude to effectively suppress electron emission therefrom and varying said field in accordance with variations desired in said 5 electron discharge.

4. The method of producing an electron discharge at a given operating voltage between electrodes, one of which emits electrons while traversed by a current of sufficient magnitude to generate a magnetic field capable of suppressing a current between said electrodes which consists in reducing the magnitude of said heating current sufficiently to reduce the magnetic field below 10 the critical value at which electron flow is prevented over periods of time so short that the temperature and electron emission of said cathode is maintained sufficiently high to produce a desired current.

15 5. The method of operating at a given impressed voltage a magnetron having a cathode requiring a heating current of such high magnitude that the electron current through said magnetron is decreased by the magneto-strictive effect which consists in 20 periodically decreasing the heating current of said cathode over intervals so short that the cathode temperature is maintained during said intervals sufficiently high to emit electrons supporting the current corresponding to the impressed voltage.

25 6. An electron discharge device comprising a cathode, an anode located about said cathode, said cathode being adapted both to emit electrons and having an electric conductivity sufficiently great to conduct a current of sufficient magnitude to produce a magnetic field which will effectively reduce an electron current between said electrodes.

30 40 7. An electron discharge device comprising an anode and a cathode, said cathode having electric conductivity and electron emissivity so related as to render said cathode capable of functioning both as a 45 source of electrons and as a means for producing a magnetic field having sufficient strength to effectively decrease an electron current between said electrodes at a given impressed voltage.

50 8. An electron discharge device provided with electrodes for producing a radial electron discharge, one of said electrodes being constructed and arranged to produce a magnetic field at angles to said discharge and having sufficient conductivity to conduct a current the magnetic field of which is sufficiently great to effectively decrease said electron discharge over a range of operating voltages, and means for periodically decreasing said field to increase said electron discharge.

55 9. An electron discharge device comprising means for producing an electron discharge and for producing a magnetic field at right angles to the general axis of said

discharge, which is of sufficient value to effectively decrease said discharge.

10. The combination of an energy source, an electron discharge device comprising a cylindrical anode, a linear cathode adapted to be heated to incandescence axially disposed within said anode, circuit connections between said source and said electrodes, the current-carrying capacity of said cathode being chosen to permit conduction of a current of sufficient magnitude to generate a magnetic field capable of effectively suppressing an electron current between said electrodes at the voltage of said source. 70

11. The combination of a source of current, an electron discharge device comprising a cathode and an anode arranged in substantially circular symmetry said cathode being adapted to emit electrons, one of said electrodes having a sufficiently high current-carrying capacity to conduct a current whereby an electron current between said electrodes may be effectively decreased by an axial magneto-strictive effect at the voltage of said source. 80

90 12. An electrical discharge device comprising an exhausted envelope and cooperating electrodes the current-carrying capacity of one of which is sufficiently high to conduct during normal operation a current capable of controlling a space current between said electrodes by an axial magneto-strictive effect.

13. An electrical discharge device comprising cooperating electrodes one of which is linear, the current-carrying capacity of said linear electrode being sufficiently high to conduct during normal operation a current capable of controlling a space current between said electrodes by an axial magneto-strictive effect. 100

110 14. An electrical discharge device comprising an exhausted envelope and two electrodes only therein, the current-carrying capacity of one of which is sufficiently high to conduct during normal operation a current capable of controlling a space current between said electrodes by an axial magneto-strictive effect.

115 15. An electrical discharge device containing two electrodes only constituted by a linear cathode, a cooperating anode symmetrically surrounding said cathode, an enclosing envelope, and means for heating said cathode, the current-carrying capacity of said cathode being sufficiently high to permit the heating current for said cathode to control the space current in said device by an axial magneto-strictive effect. 120

125 16. An electrical discharge device containing cooperating electrodes one of which symmetrically surrounds the other, the current carrying capacity of the surrounded or inner electrode being sufficiently high to carry during normal operation a current 130

capable of controlling the space current in said device by an axial magneto-strictive effect at a given voltage impressed upon said electrodes.

- 5 17. An electron discharge device which contains a cathode having a current carrying capacity so correlated with the electron emissivity of the cathode that when the cathode heating current is sufficiently great 10 to produce a temperature in said cathode at which the electron emission is substantial then the magnetic field of said current exerts an axial magneto-strictive control upon a space current in said device.
- 15 18. The combination of a work circuit, a current source therein, and an electron discharge device connected to derive current from said source, said device being provided with an electrode having a current carrying 20 capacity sufficiently high to conduct a current having a value so related to the voltage of said source that the space current in said device may be controlled by the magnetic field of said current by an axial magneto-strictive effect.
- 25 19. The combination of a work circuit, a source of electric energy therein, an electric discharge device connected to said circuit, said device having an electrode so constructed and arranged that current therethrough which will render said electrode incandescent also produces a magnetic field capable of controlling space current flow through said device by an axial magneto-strictive effect.

30 20. An electrical discharge apparatus comprising a supply circuit, means connected thereto for producing an electron discharge and for exerting an axial magneto-strictive effect sufficient to control said discharge, and means for varying said effect.

35 21. The combination of a supply circuit, an electron discharge device containing a linear cathode and a cylindrical anode symmetrically surrounding said cathode, the cathode being proportioned to carry a current sufficiently large with respect to the

voltage of said circuit to exert control by an axial magneto-strictive effect upon an 50 electron current in said device, and means for heating said cathode by a current of such magnitude that substantial electron emission is caused in addition to said magneto-strictive effect. 55

22. An electrical discharge apparatus comprising a work circuit, means connected thereto for producing an electron discharge and for exerting an axial magneto-strictive effect sufficient to control said discharge 60 and means external to said work circuit for varying said effect.

23. The combination of a work circuit, an electron discharge device connected thereto embodying means for producing an axial 65 magneto-strictive effect for controlling said discharge, a source of energy operatively connected to said device, and means for cyclically varying said magneto-strictive effect to produce desired current variations 70 in said work circuit.

24. The combination of an electron discharge device having electrodes one of which embodies means for producing an axial magneto-strictive effect, a work circuit 75 in series with the electrode capable of exerting said effect, means for delivering energy to said work circuit, an oscillation circuit connected to said electrodes, and a feed-back connection between said work circuit and said oscillation circuit.

25. The combination of an electron discharge device having an anode and a cathode which embodies means for producing an axial magneto-strictive effect, an antenna, series circuit connections between said antenna, said cathode and ground, a source of energy connected to said anode and cathode, an oscillation circuit connected in series between said source and said electrodes, and a transformer coupling between said oscillation circuit and said antenna circuit. 85 90

In witness whereof, I have hereunto set my hand this 14th day of November, 1921.

ALBERT W. HULL.
